UNITED STATES PATENT OFFICE.

GAYLORD W. BEEBE, OF MINNEAPOLIS, MINNESOTA.

CHECK-PROTECTOR.

SPECIFICATION forming part of Letters Patent No. 594,819, dated November 23, 1897.

Application filed October 25, 1895. Serial No. 566,805. (No model.)

To all whom it may concern:

Be it known that I, GAYLORD W. BEEBE, a citizen of the United States, residing at Minneapolis, county of Hennepin, and State 5 of Minnesota, have invented certain new and useful Improvements in Check-Protectors, of which the following is a specification.

My invention relates to means for indenting checks, drafts, and notes, and for inking the fiber thereof in such a manner that the 10 check-marks cannot be changed or altered without so changing the appearance thereof that the same would be noted instantly by a person seeing the check or draft.

15 The object of my invention is to provide a check-protector which shall be of an extremely simple and cheap construction and which may be operated by any person whether skilled in the use of the instrument or not, 20 and the device is designed particularly as an improvement over the check-protector shown and described in the application for Letters Patent of the United States filed by me September 17, 1894, Serial No. 523,214.

25 My invention consists generally in various constructions and combinations, all as hereinafter described, and particularly pointed out in the claims.

In the accompanying drawings, forming 30 part of this specification, Figure 1 is a plan view of a check-protector embodying my invention. Fig. 2 is a sectional view on the line *x x* of Fig. 1. Fig. 3 is a sectional view on the line *y y* of Fig. 1. Fig. 4 is a similar 35 view on the line *z z* of Fig. 2. Figs. 5 and 6 are details of the mechanism for holding the paper straight during the process of indenting the same. Figs. 7, 8, 9, 10, 11, and 12 are details of the punch-points or serrations 40 on the face of the dies.

In the drawings, 2 represents the hollow base, preferably of metal, and having the removable bottom 3, which is secured in a recess in the lower edge of the base by suitable 45 screws and is provided with rubber buttons 4 to prevent the base scratching or otherwise defacing the desk or table on which the protector may be placed. The top of the base 2 is provided on its under side with a stud 5, 50 having a central opening to receive a rod or pin 6, provided at its upper end with a disk

7, having a knob 8, into which the upper end of the rod or pin 6 extends, and a spring 9 is coiled about the pin 6 above the base and below the disk 7 and normally holds the disk 55 in a raised position.

Upon the under side of the disk 7 and near the outer edge thereof is arranged a series of dies, preferably twelve in number, mounted upon a ring 10, which is secured to said disk, 60 and each die is provided on its face with a series of beveled or cone-shaped points representing figures or characters, and beneath the disk and secured to the top of the base 2 is a removable plate or female die 11, provided 65 with a series of indentations corresponding to the serrations in the dies above and adapted to receive the same when the disk 7 is forced down against the tension of the spring 9. Beneath the opposite side of the disk is arranged 70 an inking-pad 12, which may be curved to correspond to the curve of the disk 7 and of any desired length and in position to ink the points on the face of the dies when the disk is forced down. The lower end of the pin or rod 6 is 75 provided with a collar or ring 13, securely fastened thereto, and above the ring on said pin is a bracket 14, having an extension at its outer end provided with a slotted upper end, to receive a horizontal shaft 15, which extends out 80 through the wall of the base and is adapted to move vertically in a slot 16, provided therein. The outer end of the shaft 15 is provided with a knob to be grasped by the fingers of the operator when it is desired to place a check 85 in the machine. The inner end of the shaft 15 fits into a recess 17 in the side of the stud 5, the inner end of the recess being of a size to closely fit the end of the shaft 15, while the outer part of the recess is enlarged to permit 90 the shaft to be depressed, as described. A stud 18 is provided on the under side of the top of the base, having a slotted lower end to receive and form a guide for the shaft 15. A flat spring 19 is provided having one end se- 95 cured to the inside wall of the base and its free end bearing upon the under side of the shaft and normally holding it in the upper end of the slot 16.

Upon the inner end of the shaft 15, between 100 the stud 5 and the upward extension of the bracket 14, is a ratchet 20, and a dog 21 is piv-

oted to the bracket 14, having one end in engagement with the teeth of the ratchet-wheel 20, being held in engagement therewith by the spring 22. Upon the opposite side of the 5 ratchet-wheel and secured to the under side of the top of the base 2 is a spring-dog 23, also having its end in engagement with the teeth of the ratchet-wheel, whereby the wheel is prevented from turning backward during the 10 operation of the machine.

Upon the outer end of the shaft 15 is arranged a hub 24, provided at each end with the milled wheels 25, which extend up through slots in the top of the base. The base is 15 pivoted upon its upper surface with a flange 26, surrounding the disk 7 and preventing dust and other foreign substances from getting into the dies. The flange 26 is provided with a threaded opening to receive a pin 27, which 20 extends out parallel with the top of the base and is provided with the roller 28, which normally rests upon the peripheries of the wheels 25. The roller 28 is provided with a recess in each end, thereby bringing its bearing on the 25 pin 27 at the center of the roll, and the construction permits the roll to automatically be brought to a proper and even bearing upon the surfaces of the wheels 25. The hub 24 is held in position on the shaft 15 by a suitable 30 set-screw, and a collar 29 is arranged on the shaft just inside the depending stud 18.

In Figs. 1 and 3 I have shown a device for guiding the paper during the process of indentation and thereby assuring perfect alignment. This device consists of a long arm 31, pivoted to the inside wall of the base 2 and extending over and resting upon the shaft 15, as shown in Fig. 3. This arm is provided at its free end with a roller 32, which extends a 35 short distance above the upper surface of the top of the base through a slot or opening therein. The roller 32 is provided with annular grooves 33 to receive ribs 34, provided on a roller 35, which is supported by the flange 26. When the shaft 15 is depressed, the arm 31 will drop with it and leave a space between the rolls 32 and 35 to permit the insertion of the end of a check or draft, and when the shaft is released the spring beneath 40 the same will raise the shaft and arm back to their normal position and keep the paper straight during the process of indenting. While I consider this device a valuable addition to the machine, I do not confine myself 45 to its use, as it may be dispensed with, if desired.

I provide a guide for the check as it is being put into the machine, which consists in a slotted arm 36, held in place by a thumb-screw 37, which enters a threaded opening in the flange 26. The disk 7 is provided upon its upper surface with characters corresponding to the serrated outlines on the dies beneath, and the periphery of the disk 7 is provided with recesses 36' to receive a spring-catch 37', carried by the top of the base, and which serves to hold the disk in position when

it is being depressed to indent the check or draft. A lug 38 is also provided on the top of the base, which prevents the disk from revolving while being depressed and also prevents the disk from being depressed except when one of the dies carried by said disk is over the female die.

A stopper 39 is provided upon the upper 75 surface of the disk near its periphery, through which ink is supplied to the pad below, and the knob 8 is also provided with projections which prevent the hand from slipping while 80 turning the disk.

A set-screw 42 is provided in the bracket 14 to extend up through the same and engage the teeth of the ratchet-wheel 20. This screw acts as a stop and regulates the movement of the ratchet-wheel, preventing the same from 85 moving forward more than the desired distance at each upward movement after each depression of the disk. The screw also serves to support the spring which keeps the dog 21 in engagement with the teeth of the ratchet-wheel.

The punching points or serrations may be continuous, as shown in Figs. 8 and 9, or may be made with a space between every two points, as shown in Fig. 7, and, as shown in 95 this figure, the depressions in the female die are preferably made larger in diameter than that of the punch-points, so that the paper will not be cut when it is forced into the depressions in the female die, but only crushed 100 and indented. The top of the base is made crowning, as clearly shown in Fig. 3, so that all danger of smearing the face of the check or draft with ink during the process of indenting the same will be avoided.

Whenever it is desired to ink the pad, the plug or knob 39 is removed and the ink applied by a brush upon the pad through the opening in the top of the disk.

The operation of the device is as follows: 110 When it is desired to indent a check or draft, the shaft 15 is depressed and the end of the slip of paper inserted between the guiding-rolls and also between the milled wheels and the roller 28, the guide 37 serving to bring the paper to the right position. The flange 26 being slotted upon both sides of the female die 11, the edge of the paper will slip in under the dies carried by the disk 7, and when the desired point is reached the disk is depressed and the serrated face of the die immediately above the female die forced into the check or draft. As the rod 6 rises after 115 being depressed the ratchet mechanism is operated and the milled wheels revolved, thereby advancing the paper farther into the machine to present a new place for indentation. When the desired indentations have been 120 made, the shaft may be depressed again and the paper removed. The indented portions 130 of the paper being thoroughly inked, it will obviously be impossible to alter the characters so indented in the face of the paper without detection. This indentation and abrasion

of the paper is particularly insured by using slightly-blunted points, as shown in Figs. 11 and 12.

Having thus described my invention, I claim as new and desire to secure by Letters Patent—

1. In a device of the class described, the combination, with a suitable base, provided with an annular flange upon its upper surface, of a revoluble and vertically-movable shaft supported by said base, a disk carried by said shaft and arranged within said flange, and provided with a series of dies and with a series of notches in its edge, and a spring-dog arranged in a recess in said flange and adapted to engage the notches in said disk, for the purpose specified.

2. In a device of the class described, the combination, with a suitable base provided with an upright circular flange or wall, a rotating disk mounted upon an upright vertically-movable shaft and substantially filling the space within said wall or flange, and provided with a series of dies upon its under surface and with a series of notches in its edge, a spring arranged within said wall and engaging said notches, and means for inking said dies, for the purpose set forth.

3. The combination, with the suitable base, provided with an annular flange upon its upper surface, of a revoluble disk supported by said base within said flange, dies upon said disk, a plate or female die carried by the base beneath said disk, an inking-pad also arranged upon the base beneath the disk, said disk being provided with an opening through which said pad may be inked, for the purpose set forth.

4. In a device of the class described, the combination with a hollow base, of a revolving vertically-movable disk arranged thereon, a rod whereon said disk is supported, a horizontal shaft arranged within said base, a ratchet carried thereby, a dog carried by said

rod and engaging with said ratchet, a wheel 45 carried by the outer end of said shaft, vertically movable therewith, and extending up through openings in the top of said base into engagement with a roller arranged thereon, a series of dies carried by said disk and provided with serrations forming characters corresponding to characters marked upon the upper surface of said disk, a movable plate or female die arranged beneath said disk, and provided with indentations to receive the serrations on the face of said dies when said disk is depressed, and means for inking said dies, substantially as described.

5. In a device of the class described, the combination with the base, of the vertically-movable revolving disk mounted thereon, a rod or shaft supporting said disk, the bracket upon the lower end thereof, a horizontal shaft having one end extending through the wall of said base, the ratchet-wheel upon the inner end thereof, the dog carried by said bracket for engaging the teeth of said ratchet during the upward movement of said disk, the wheel arranged upon the outer end of said shaft and extending up through the top of 70 said base, the roller above said wheel, the spring for normally holding said wheel in engagement with said roller, and permitting said shaft and wheel to be depressed to insert the paper between said wheel and said roller, the 75 female die arranged beneath said disk, a series of dies carried by said disk, means for inking the same, and a guide for preventing said disk from turning while being depressed, and the spring for normally holding said disk in a 80 raised position substantially as described.

In testimony whereof I have hereunto set my hand this 26th day of September, A. D. 1895.

GAYLORD W. BEEBE.

In presence of—

A. C. PAUL,

C. G. HAWLEY.
